UNITED STATES PATENT OFFICE.

WILLIAM C. HOUSHOLDER AND JOHN P. WIEDENHOFER, OF PITTSBURGH, PENNSYLVANIA.

THERMOSTAT-CONTROLLED VALVE.

Application filed April 11, 1922. Serial No. 551,459.

To all whom it may concern:

Be it known that we, WILLIAM C. HOUSHOLDER and JOHN P. WIEDENHOFER, citizens of the United States, residing at Pittsburgh, in the county of Allegheny and State of Pennsylvania, have invented certain new and useful Improvements in Thermostat Controlled Valves, of which the following is a specification.

10 This invention is for an improvement in thermostatic controlled valves particularly adapted for controlling the flow of fuel to the burner of a water heater, but capable of use with various kinds of devices where 15 thermostatic controlled valves are necessary.

The present invention has for its primary object to provide a valve which will operate in both directions with a quick or snap action, that is, without requiring the lapse of 20 any appreciable length of time when moving from one position to the other, so that the valve is either tightly closed or wide open, the snap action being attained solely by mechanical means without relying on 25 the pressure of the fluid passing through the valve or without resort to magnetic or electrical means; the construction of the valve being simple and its actuation positive.

Our invention may be readily understood 30 by reference to the accompanying drawings, in which:

Fig. 1 shows our valve applied to a water tank of a common form of water heater;

Fig. 2 is a bottom elevation of the valve 35 and its associated mechanism with part of its housing removed;

Fig. 3 is a transverse longitudinal section on line III—III of Fig. 2; and

Fig. 4 is a transverse vertical section in the 40 plane of line IV—IV of Fig. 3.

In the drawings, A represents the hot water tank; B, the valve; and C, the heater.

The valve comprises a casing composed of two sections 5 and 6. The upper section 5 45 has an integral threaded extension 7 which attaches to the water tank and which carries a hollow expandable element, such as a copper tube 8. The outer extremity of this tube is closed, and inserted in the tube, 50 through an opening in the extension 7, is a rod 9 of porcelain or other material having a minimum co-efficient of expansion under heat.

Pivoted at 10 in the casing 5 is a lever 11 55 against which the inner end of the porcelain

rod 9 bears, the point of contact being near the pivot 10. The other end of lever 11 is pivotally connected at 12 to lug 13 near one end of lever 14. Lever 14 has a cross head 15 at its opposite end, on which are two spaced apart rounded cam surfaces 16. A set screw 17 in the casing member 6 bears against the end of lever 14 adjacent lug 13, and provides an adjustable fulcrum for lever 14. A spring 18 serves to oppose the action of the thermostat elements 8 and 9.

Bearing against the cam faces 16 are set screws 19 on L-shaped arms 20. These arms are fixed on a leaf spring 21 which extends across the casing transversely, and has one end abutting against the side of casing 5, while its other end abuts against a vertical leaf spring 22. Passing through the leaf spring 21 is the stem 23 of valve 24. The spring is disposed between upper and lower 75 spaced apart nuts 25 on the threaded stem 23. Spring 21 always tends to bow, as shown in Fig. 4. The leaf spring 21 is disposed transversely to the direction of movement of the valve.

The valve stem 23 extends through the valve 24, the upper end of which is designated 23^a being slidably received in a bore in the casing. On the portion 23^a of the stem is a spring 26 which serves to frictionally engage the sides of the bore to hold the valve against independent movement.

On the upper face of the cross head 15 are adjustable lugs or screws 27, for the purpose hereinafter described.

The casing member 6 is bolted to member 5 by bolts or screws 5^a passing through lugs on the respective casing members. A sealing gasket 28 may be interposed between the 95 casing sections.

The gas inlet pipe is designated as 30, and 31 is the inlet port. The valve seat is at 32 and the outlet passage to the burner is indicated by numeral 33. The pipe leading to the burner is designated at 34. By-pass 100 35 controlled by needle valve 36 allows gas to flow to the burner at all times to provide a pilot light.

In operation, the tube 8 extends into the tank A. When the water therein cools, the 105 copper tube 8 contracts in length, causing the porcelain rod 9 to push against lever 11. Levers 11 and 14 multiply this movement, which is very slight, to cause the cross head 15 to move an appreciable dis-

tance against the compression of spring 18. The leaf spring 21 is then bowed upwardly, as shown in dotted lines in Fig. 4, the valve being closed. As the cross head moves 5 gradually downwardly, the set screws 19 on the L-shaped levers 20 ride down on the inclined cam surfaces 16, tending to straighten leaf spring 21. Leaf spring 22 yields to compensate for the straightening 10 out of the spring 21. During this time, the leaf spring 21 will move between nuts 25 without moving the valve. As the leaf spring 21 reaches dead center, it will snap downwardly into the full line position of 15 Fig. 4, at the same time engaging the lowermost nut 25 to move the valve a corresponding distance, the valve then being wide open. In this position, the leaf spring 21 will engage the heads of screws 27 on the 20 cross head 15.

Immediately upon the valve being opened, the water in the tank will begin to be heated. As its temperature rises, the copper tube will expand. Spring 18 will 25 then act to move the cross head 15 in the opposite direction, upwardly. The heads of screws 27 pushing up on leaf spring 21 moves it toward dead center. When it reaches this position, the spring bows upwardly with a snap, moving the valve with 30 it to closed position.

By adjusting nuts 25, screws 19 and 35 screws 27, various modulations in the action of the valve can be obtained. Also, adjustment of the variation of temperatures between which the valve will act can be obtained by turning screw 17. Adjustment of screw 17 determines the critical 40 position of the cross head at which the valve will snap open or closed by limiting the movement of lever 14. Except when large quantities of water are drawn from the tank, the temperature thereof may be kept constant within a very few degrees.

By adjustment of nuts 25, the valve 45 could be made slow-acting in one direction and quick-acting in the other, or slow in both. It is desirable in most instances, however, that the action be quick in both 50 directions.

From the foregoing, it will be seen that the valve is simple and can be cheaply constructed. The actuation of the valve is positive and does not depend on the 55 pressure of the gas flowing through the valve. Various changes may be made in the details of construction of the valve within the scope of our invention, and within the scope of the appended claims.

60 We claim as our invention:

1. A thermostat controlled valve comprising a casing, a thermostat associated therewith, levers in said casing arranged to be moved in accordance with the expansion 65 and contraction of the thermostat, a leaf

spring having its ends confined by supporting means carried by the casing to hold it in a normally bowed compressed position and movable transversely of its length past its dead center from a bow in one direction 70 to a bow in the other, means on said levers engaging said spring for effecting such transverse movement of the spring, and a valve actuated by said spring, said spring having a limited relative movement with respect to the levers and with respect to the valve. 75

2. A thermostat controlled valve comprising a casing, a thermostat associated therewith, a lever in said casing arranged to be moved in accordance with the expansion and contraction of the thermostat, a valve, yieldable means movable relatively to the valve, and the lever for transmitting motion from the lever to the valve, a lost motion adjustment for said yieldable means, whereby the lever may move a predetermined distance before moving the valve to put said yieldable means under compression, said yieldable means when sufficiently compressed 80 serving to actuate the valve to relieve its compression. 85

3. A thermostat controlled valve including a casing, a thermostat associated therewith, a lever in said casing actuated through the expansion and contraction of the thermostat, a valve, and a resilient means carried by the casing connecting the thermostat and the valve, said resilient means being movable relatively to the valve and to the lever to a limited extent to provide a lost motion between the two but being movable with one when moving relatively to the other, said resilient means having two extreme limits of movement, toward one or the other of which it is urged by its own resiliency when intermediate the limits of movement, said lever serving to move said resilient means away from one limit of its movement to cause it to spring to the other. 100 110

4. A thermostat controlled valve comprising a casing, a thermostat associated therewith, a lever in said casing arranged to be moved in accordance with expansion and contraction of the thermostat, a reciprocable 115 valve, means for transmitting motion from the lever to the valve having a resilient element associated therewith and having a limited movement relatively to the valve, said means being movable in an arc, the limit of 120 which is defined by the open and closed position of the valve, said means being arranged to be moved through the first portion of its travel in either direction by said lever and relatively to the valve and against 125 the action of the resilient element, the remaining portion of the movement being effected by the resilient element.

5. A thermostat controlled valve comprising a casing, a thermostat associated 130

- therewith, a lever actuated through the expansion and contraction of said thermostat, a reciprocable valve, a leaf spring supported by the casing disposed transversely to the direction of movement of the valve, said spring having a limited movement relatively to the valve, said spring having two extremes of movement toward one or the other of which it is urged by its own resiliency when moved to an intermediate position by the lever, and means having a limited movement relatively to the lever for transmitting motion from the lever to the spring, said spring being movable with the valve when moving relatively to the lever, and vice versa.
6. A thermostat controlled valve comprising a casing, a thermostat associated therewith, a lever in the casing actuated through the expansion and contraction of the thermostat, a reciprocable valve, a leaf spring disposed transversely to the direction of movement of the valve and loosely connected therewith in such manner that it may have a limited movement relatively to the valve, said leaf spring being arranged to normally assume a bowed position, and means for transmitting motion from the lever to the spring to move it to a central position tending to straighten the spring, whereby it will snap into a bowed position reverse to that from which it previously assumed, said spring moving relatively to the valve when being moved to the central position and moving the valve when snapping to the bowed position.
7. A thermostat controlled valve comprising a casing, a thermostat associated therewith, a lever in the casing actuated through the expansion and contraction of the thermostat, a reciprocable valve, a leaf spring disposed transversely to the direction of movement of the valve and loosely connected therewith in such manner that it may have a limited movement relatively to the valve, said leaf spring being arranged to normally assume a bowed position, yieldable means at one end of the spring for yieldably holding it in a bowed position, and means for transmitting motion from the lever to the spring to move it to a central position tending to straighten the spring, whereby it will snap into a bowed position reverse to that from which it previously assumed, said spring moving relatively to the valve when being moved to the central position and moving the valve when snapping to the bowed position.
8. A thermostat controlled valve comprising a casing, a thermostat associated therewith, a lever in the casing actuated through the expansion and contraction of the thermostat, a reciprocable valve, a leaf spring disposed transversely to the direction of movement of the valve and loosely connect-
- ed therewith in such manner that it may have a limited movement relatively to the valve, said leaf spring being arranged to normally assume a bowed position, a second leaf spring against which one end of said first leaf spring abuts and disposed transversely to the said first leaf spring, and means for transmitting motion from the lever to the spring to a central position tending to straighten the spring, whereby it will snap into a bowed position reverse to that from which it previously assumed, said spring moving relatively to the valve when being moved to the central position and moving the valve when snapping to the bowed position.
9. A thermostat controlled valve comprising a casing having inlet and outlet passages, a thermostat carried by the casing, levers in the casing actuated through the expansion and contraction of the thermostat, a spring acting in opposition to the thermostat, a reciprocable valve for opening and closing the outlet passage of gas through the casing, a stem on said valve, a leaf spring disposed transversely to said stem and engaging between spaced apart nuts thereon, said leaf spring being arranged to normally assume a bowed position, and means for transmitting motion from one of said levers to said spring to effect an actuation of the valve.
10. A thermostat controlled valve comprising a casing having inlet and outlet passages, a thermostat carried by the casing, levers in the casing actuated through the expansion and contraction of the thermostat, a spring acting in opposition to the thermostat, a reciprocable valve for opening and closing the outlet passage of gas through the casing, a stem on said valve, a leaf spring disposed transversely to said stem and engaging between spaced apart adjustable nuts thereon, said leaf spring being arranged to normally assume a bowed position, and means for transmitting motion from one of said levers to said spring to effect an actuation of the valve.
11. A thermostat controlled valve comprising a casing, a thermostat carried thereby, a reciprocable valve, a lever arranged to be rocked by the thermostat, and a leaf spring carried by the casing for transmitting motion from the lever to the valve, said spring having a limited movement relatively to the valve during the time it is being moved by the lever, and having a movement relatively to the lever when it is actuating the valve.
12. A thermostat controlled valve mechanism including a casing, a thermostat carried thereby, a lever arranged to be rocked by the expansion and contraction of the thermostat, a pair of cam faces on the free end of said lever on one side thereof, pro-

jecting means on the other side thereof, a reciprocable valve, a leaf spring disposed transversely to the direction of movement of the valve and having a limited movement relatively thereto, said leaf spring being arranged to move the valve after it has moved a predetermined distance, levers on said leaf spring having means thereon engaging the cam faces for moving the spring in one direction, said projecting means on the other side of said lever being for the purpose of moving the spring in the opposite direction.

13. A thermostat controlled valve comprising a casing, a thermostat carried thereby, a reciprocable valve, a lever arranged to be rocked by the thermostat, an adjustable fulcrum for said lever, and a normally bowed leaf spring carried by the casing for transmitting motion from the lever to the valve, said spring having a limited movement relatively to the valve during the time it is being moved by the lever, and having a movement relatively to the lever when it is actuating the valve.

14. A thermostat controlled valve mechanism including a casing, a thermostat carried thereby, a lever arranged to be rocked by the expansion and contraction of the thermostat, an adjusting screw for varying the operation of the lever, a pair of cam faces on the free end of said lever on one side thereof, projecting means on the other side thereof, a reciprocable valve, a leaf spring disposed transversely to the direction of movement of the valve and having a limited movement relatively thereto, said leaf spring being arranged to move the valve after it has moved a predetermined distance, levers on said leaf spring having means thereon engaging the cam faces for moving the spring in one direction, said projecting means on the other side of said lever being for the purpose of moving the spring in the opposite direction.

15. A thermostat controlled valve mechanism including a casing, a thermostat carried thereby, a lever arranged to be rocked by the expansion and contraction of the thermostat, a pair of cam faces on the free end of said lever on one side thereof, projecting means on the other side thereof, a reciprocable valve having a stem, a normally bowed leaf spring through which the valve stem passes disposed transversely to the direction of movement of the valve and having a limited movement relatively thereto between adjustable nuts on the valve stem, said leaf spring being arranged to move the valve after it has moved a predetermined distance, levers on said leaf spring having means thereon engaging the cam faces for moving the spring in one direction, said projecting means on the other side of said lever being for the purpose of moving the spring in the opposite direction.

16. A thermostat controlled valve mechanism including a casing, a thermostat carried thereby, a lever arranged to be rocked by the expansion and contraction of the thermostat, a pair of cam faces on the free end of said lever on one side thereof, projecting adjustable screws on the other side thereof, a reciprocable valve, a leaf spring disposed transversely to the direction of movement of the valve and having a limited movement relatively thereto, said leaf spring being arranged to move the valve after said leaf spring has moved a predetermined distance, levers on said leaf spring having adjustable screws thereon engaging the cam faces for moving the spring in one direction, said projecting adjustable screws on the other side of said lever being for the purpose of moving the spring in the opposite direction.

17. A thermostat controlled valve comprising a casing, a thermostat associated therewith, a lever actuated through the expansion and contraction of said thermostat, a reciprocable valve, a leaf spring disposed transversely to the direction of movement of the valve, said spring having a limited movement relatively to the valve, means on said valve for preventing movement thereof independently of the leaf spring, and means with respect to which the spring is relatively movable for transmitting motion from the lever to the spring.

18. A thermostat controlled valve comprising a casing, a thermostat associated therewith, a lever in the casing actuated through the expansion and contraction of the thermostat, a reciprocable valve, a leaf spring disposed transversely to the direction of movement of the valve and loosely connected therewith in such manner that it may have a limited movement relatively to the valve, said leaf spring being arranged to normally assume a bowed position, means for transmitting motion from the lever to the spring to move it to a central position tending to straighten the spring, whereby it will snap into a bowed position reverse to that from which it previously assumed, said spring moving relatively to the valve when being moved to the central position and moving the valve when snapping to the bowed position, and means on said valve for frictionally holding it against movement relatively to the spring.

19. A thermostat controlled valve comprising a casing having inlet and outlet passages, a thermostat carried by the casing, levers in the casing actuated through the expansion and contraction of the thermostat, a spring acting in opposition to the thermostat, a reciprocable valve for opening and closing the outlet passage of gas through the casing, a stem on said valve, a leaf spring disposed transversely to said stem and en-

gaging between spaced apart nuts thereon, said leaf spring being arranged to normally assume a bowed position, a spring on the valve stem for frictionally holding the valve 5 against independent movement, and means for transmitting motion from one of said levers to said spring to effect an actuation of the valve.

20. A thermostat actuated valve including 10 a lever, a valve, a leaf spring arranged to

always seek a bowed position interposed between the lever and valve for transmitting motion from the former to the latter, and resilient supporting means mounted in the casing, at one end of said leaf spring for 15 yieldably allowing the spring to straighten.

In testimony whereof we affix our signatures.
